Primary Examiner—Bernard Ansher*Assistant Examiner*—Philip Hyder*Attorney, Agent, or Firm*—Dougherty, Hessin, Beavers & Gilbert[57] **CLAIM**

The ornamental design for a hollow shaft puller, as shown and described.

DESCRIPTION

FIG. 1 is an exploded isometric view of a hollow shaft puller, showing my new design;

FIG. 2 is a front elevational view thereof, the rear elevational view being the mirror opposite thereto;

FIG. 3 is a top plan view thereof;

FIG. 4 is a right side elevational view thereof;

FIG. 5 is a left side elevational view thereof; and,

FIG. 6 is a bottom plan view thereof.
